(57) **CLAIM**

The ornamental design for a glass solar panel, as shown and described.

DESCRIPTION

FIG. 1 is a front view of a glass solar panel according to the claimed design;

FIG. 2 is a perspective view thereof;

FIG. 3 is a front view of another embodiment of a glass solar panel according to the claimed design;

FIG. 4 is a perspective view thereof;

FIG. 5 is a front view of another embodiment of a glass solar panel according to the claimed design;

FIG. 6 is a perspective view thereof;

FIG. 7 is a front view of another embodiment of a glass solar panel according to the claimed design;

FIG. 8 is a perspective view thereof;

FIG. 9 is a front view of another embodiment of a glass solar panel according to the claimed design;

FIG. 10 is a perspective view thereof;

FIG. 11 is a front view of another embodiment of a glass solar panel according to the claimed design;

FIG. 12 is a perspective view thereof;

FIG. 13 is a front view of another embodiment of a glass solar panel according to the claimed design;

FIG. 14 is a perspective view thereof;

FIG. 15 is a front view of another embodiment of a glass solar panel according to the claimed design; and,

FIG. 16 is a perspective view thereof.

The broken lines shown in the drawings represent portions of the glass solar panel that form no part of the claimed
